UNITED STATES PATENT OFFICE.

JAMES F. THOMAS, OF MONTREAL, QUEBEC, CANADA.

POWER-GENERATING MECHANISM.

Application filed June 4, 1925. Serial No. 34,962.

To all whom it may concern:

Be it known that I, JAMES F. THOMAS, a subject of the King of Great Britain, residing at Montreal, Province of Quebec, Dominion of Canada, have invented certain new and useful Improvements in Power-Generating Mechanism, of which the following is a specification.

This invention relates to mechanism particularly adapted for compressing air and incidentally heating water for use in various capacities as a power generating medium, or for general compressed air and hot water service or supply, and the primary object of the invention is to provide a comparatively simple organization of operating elements of the rotative type disposed at different angles on a driven shaft and including gravitating means for operating pistons mounted in cylinders associated with each complete compressing unit, and also to operate the units in sequence to set up a constant supply of compressed air which is aggregated from all of the units and delivered to and from a conduit or pipe to any point of service that may be desired.

A further object of the invention is to provide a mechanism of the class specified comprising as a prime factor a compressing unit fixed to and rotatable with a driving shaft and having a dual compressing function in one complete revolution of the unit and shaft, and wherein all of the parts are so associated as to automatically and effectively operate in the performance of air compression and discharge of the compressed air and utilization of the heat of the compressed air by radiation to raise the temperature of water for other uses and service.

A further object of the invention is to provide mechanism of the class specified that will effectively compress air and incidentally heat water with a minimum amount of actuating power and a consequent minimum cost of fuel by producing an automatic operation through gravitating means for actuating the pistons of alternately acting cylinders carried as a part of and rotating with each unit and wherein the cylinders have a self-charging and discharging operation.

A still further object of the invention is to minimize the friction of the actuating units or compressing means and so mount the latter as to set up a self-restoration to

normal starting position and in position for a continuous actuation of the distinct air compressing cylinders and pistons without requiring the least manual attention or use of complicated mechanism to control the regular action of the pistons and cylinders in the performance of their desired functions.

With the foregoing and other objects and advantages in view, the invention consists in the construction and arrangement of the several parts which will be more fully hereinafter described and claimed.

In the drawings:

Fig. 1 is a side elevation of the improved mechanism, showing one unit in longitudinal vertical section and the shaft and a portion of the unit hubs in cross section.

Fig. 2 is a side elevation of the improved mechanism, showing the supporting means including a pit in section and also illustrating a portion of the driving mechanism for the main shaft of the improved device.

Fig. 3 is a side elevation of the intermediate body and weight organization of each unit and illustrating one of the side closure plates removed and the weight means in dotted lines.

Fig. 4 is a transverse vertical section on the line 4-4, Fig. 3.

Fig. 5 is an elevation of a portion of the frame structure and one end of one of the unit hubs.

Fig. 6 is an end elevation of one of the units with the compressing cylinder and piston removed and also the weight and intermediate frame organization, to particularly illustrate the manner of assembling the anti-frictional attachment for the movable parts.

Fig. 7 is a longitudinal vertical section through one of the water heating attachments or gland elements.

The improved mechanism may be supported by any suitable means but is preferably mounted on a concrete or cement support 5 having a pit 6 formed therein of such dimensions as to accommodate the unrestricted rotation of the compressing units or elements, which will be hereinafter described. In suitable bearings 7 disposed on the support 5 a tubular shaft 8 is mounted to rotate and has fixed thereto a gear 9, held in continual mesh with a drive gear 10 mounted on a shaft 11 driven from any suitable source of power. The gears 9

and 10 may be proportioned to produce the requisite rotation of the shaft 8 to the best advantage and this gear mechanism is illustrative of only one means by which the shaft 5 may be rotated, as it is obvious that other mechanism may be adopted at will. On the shaft 8 in regular spaced relation are a plurality of air compressing units A B and C, all of duplicate construction or embodying precisely the same features and all similarly operating. These compressing units as shown by Fig. 1 are disposed on the shaft 8 at predetermined varying angles relatively to each other, and in lieu of three units 10 A B and C as shown, it is obvious that the number may be increased or decreased in accordance with the capacity of the improved mechanism that may be desired. One of the units will be particularly described in detail and the remaining units will have similar reference characters applied to like parts. All of the units are secured to the shaft 8 by means of hubs, generally designated by 12, and each comprising two sections 13 and 14, which have their inner ends abutting as shown by Fig. 6 and their outer ends flanged as at 15 for securing the same by any suitable fastening means as a unitary elongated sleeve structure over the shaft and thus reinforce the mounting of the units relatively to the shaft. The hubs are keyed to the shaft 8 by suitable grooves and keys, as at 16, Fig. 1, so that the said hubs will all equally 25 rotate with the shaft 8. Extending centrally through the shaft 8 is a conduit or pipe 17, the said pipe being of less diameter than the interior diameter of the shaft 8, to provide an annular space 18 between the 30 pipe and shaft.

Each unit comprises an intermediate or centrally located gravitating body generally designated by 19 and comprises upper and lower weight chambers 20 and 21, having 35 therein lead or other weight fillings 22 and 23 and a central open space 24 having side plates 25, which are extended beyond the ends of the said body member as at 26 for a purpose which will be presently explained.

The upper and lower weight chambers are 40 enclosed by bottom and top plates 27 and 28 and the weight chambers at the ends have closures in the form of I-plates 29, to maintain the lead or other weight filling in place. The hub sections 12 and 13 of each 45 unit extend transversely through the centers of the open spaces 24, which may be termed a sliding chamber, the entire body 9 having a sliding movement in opposite directions in accordance with the position of the latter during the rotation thereof. Within the opposite ends of the central slide 50 chamber, which is longitudinally straight, angle plate closures 30 are fixed, and within the outer recessed sides 31 of these closures

rubber or other buffers 32 are suitably secured. Within the open space or slide chamber 24 close to the end closures 30 are angular bearing brackets 33, preferably of the form shown by Fig. 1, and through the 55 said closures 30 openings 34 are formed as clearly shown by Figs. 3 and 4, these openings 34 being in central relation to openings 35 formed in the cushions or buffers 32. The side plates 26 of the intermediate 60 open space or slide chamber 24 are extended outwardly beyond the ends of the said open space or chamber, and the intermediate body 19 at its central portion moves between the extensions of these plates. Secured to the 65 plates 26 on opposite sides of the shaft 8 and the hub 12 are guides having opposite spaced side members 36, which are secured to the hub sections 13 and 14 and are connected at their upper and lower ends by 70 cross bolts or tie devices 37, to maintain the said side members 36 in accurate spaced relation. Between the upper and lower ends of the side members 36 of the guides and close to the connecting or tie bolts 37 are 75 anti-frictional rollers 38, which engage the upper and lower plates of the weight chambers 20 and 21, the inner plates of these weight chambers which define the open space or slide chamber 24 being out of contact with and freely movable over the hub sections 13 and 14, and by means of these rollers the friction incident to the reverse longitudinal shifting movement or sliding action of the intermediate body 19 is reduced to a minimum and the said body as a 80 whole is given a sensitive operation, or is always quickly responsive to sliding movement through gravitation when the said body and parts associated therewith are 85 turned to different angles by the rotation thereof with the shaft 8.

The side plates 26 which project or extend beyond the opposite maximum projecting terminals of the intermediate body 19 have 90 mounted therebetween compressing cylinders 39, which are held fixed and each has a piston 40 mounted therein and connected to a piston rod 41 projecting through the inner 95 open end of its cylinder and also through the openings 35 and 34 of the cushions or buffers 32 and end closure 30 of the central open space or slide chamber 24. The inner ends of the piston rods 40 are formed with joint heads 42, which are movably held between the bearing brackets 33 by pivot pins 43. The inner ends of the cylinders 39 are 100 equally spaced from each terminal of the intermediate sliding body or frame 19 and the limit of sliding movement of the said body in opposite directions is governed by the inner termination of the said cylinders, the cushions or buffers 32 striking the inner 105 ends of the cylinders when the intermediate body 19 reaches the limit of its movement in 110

reverse directions. It will be understood that the pistons 40 will be suitably packed or ringed to render the same air-tight relatively to the walls of the cylinders in which they work, and the said cylinders have outer closed ends 44 with separate ports 45 and 46 therethrough, said ports being formed with suitable valve seats for an outwardly opening valve 47 and an inwardly opening valve 10 48, respectively operating with the ports 45 and 46 and having stems 49 mounted in suitable bearing devices 50 in chambers 51 of a head 52 secured to the outer closed end 44 of each cylinder, the chambers 51 being provided by a central partition 53. The outer end of each head 52 has an air inlet port 54, and connected to the remaining chamber of this particular head is a discharge pipe 55, the two discharge pipes 55 from the opposite 20 heads of the cylinders connecting with a central pipe 56 which extends through the hub 12 and shaft 8 and communicates with the pipe 17.

The shaft 8 at its opposite extremities 25 passes through opposite gland means 57 and 58 located a suitable distance outside of the bearings 7 for the said shaft, the gland means 57 being in the form of a water inlet and having a supply pipe 59 connected thereto, and the gland 58 serving as a discharge or outlet means and having a discharge pipe 60 connected thereto. Adjacent the gland means 57 the end of the shaft is closed by a suitable plug construction of a 30 water-tight character, as at 61, the opposite end of the shaft as at 62 being closed by any suitable means around the pipe 17, which continues outwardly at this extremity of the shaft and is held by a suitable support 63.

The gland means 57 and 58 and the support 40 63 are all mounted on the main support 5 as shown by Fig. 2. Each gland means as shown by Fig. 7 has a central annular core or body 64 and outer closing plates 65, between which and the body suitable packing material 66 is interposed to form a tight joint, the adjacent sides of the core or body 64 and the plate 65 being recessed and corrugated, as at 67 and 68, to effectively lock or 45 secure the packing 66 between the core or body 64 and the plate 65, the latter elements being secured as shown by cross bolts 69 and 70. The core or body 64 has a reduced annular chamber 71 with a port 72 extending 50 outwardly through the gland means and to which either the pipe 59 or 60 has communication. Each annular chamber 71 also has communication with the annular space or chamber 18 between the shafts 8 and pipe 17 through the medium of a port or 55 opening 73. Water supplied through the pipe 59 of the gland means 57 will pass into the annular chamber 18 of the shaft 8 around the pipe 17, and is 60 heated by the heat conducted from the pipe 65.

17 and the compressed air passing through the latter, and by this means the heat generated by compressing the air and entering the pipe 17 will be utilized with economy in heating water supplied to the chamber 18 of the shaft 8 and discharged through the pipe 60 to any point desired, it being understood that said pipe may be projected away from the improved mechanism any suitable distance for utilization of the heated water.

The several parts and the shapes thereof necessary in the construction of the improved mechanism as described may be varied, and channel irons and parts of the latter will be utilized together with flat plates, all preferably of metal, and the structure of the several parts will also be simplified as much as possible to reduce the cost of construction and assemblage of the parts, and furthermore, it is intended to use fastening means for the several parts best adapted for the purpose and which will require the least amount of labor to apply the same. The packing 66 shown by Fig. 7 may not only be of a character to form a tight joint between the plates 65 and the core or body 64, but may also be of a heat non-conducting character especially in connection with the gland means 58 from which the heated water is discharged.

The operation of the improved mechanism is very simple. Power is transmitted through the shaft 11 to the gear 10 and from the latter gear to the gear 9 and the shaft 8 thereby rotated. The rotation of the shaft 100 may be in either direction, or to the right or left, as the units A B and C will operate equally well in either direction specified. Assuming that the mechanism starts from the position shown by Fig. 1 and is rotated 105 to the right, all the units uniformly rotate and the unit A, for instance, gradually rises until it assumes an angle of inclination whereby the weight elements 20 will cause the intermediate body or frame 19 to slide 110 downwardly towards the right, thereby forcing the piston 40 of the cylinder 39 at the right into said cylinder and close the valve and its stem 48 and open the valve and its stem 47, and what little air may be within the right cylinder at the beginning of the operation will be forced outwardly into the pipe 55 and from the latter by way of the pipe 56 to the pipe 17. At the time this operation of the cylinder at the right ensues, the same cylinder and piston organization at 115 the left will be reversely operated, or the piston 40 thereof will be drawn inwardly, thereby opening the valve and its stem 48 and closing the valve and its stem 47, and this left cylinder under this operative condition will be charged with air through the port 54. As the sliding body 19 moves 120 around to the right, the right-hand cushion or buffer 32 will contact with the inner end 125 130 of the cylinder 39.

of the right cylinder 39, and a half revolution of the body or frame 19 with the cylinders and pistons will bring the right-hand cylinder 39 to the left and that at the left 6 to the right with the pistons in reverse positions, or the right-hand piston 40 fully forced outwardly and the left-hand piston 40 as shown by Fig. 1 fully drawn inwardly in its cylinder, and a continuance of the rotation 10 will cause a reverse sliding action of the body or frame 19 and force out the piston 40 then at the right of the mechanism and draw the piston 40 at the left of the mechanism to charge the then left-hand cylinder and discharge the air from the then right-hand cylinder into the pipe 55, so that in one complete revolution two compressing and charging actions are effected. This same operation proceeds regularly in the remaining units B and C and all of the air 20 drawn into the respective cylinders and discharged therefrom passes into the pipes 55 and by way of the pipe 56 to the central discharge pipe 17, and the compression of the air is cumulative within the pipe 17. Compression of the air ensues through the pipes 55, 56 and 17, the pipes 55 and 56 being reduced in diameter or rendered comparatively small so as to create a friction as well as a 25 close confinement of the air discharged from the cylinders into the said pipes, and this friction will obviously generate heat and the heat radiated from the pipe 17 will be taken up by the water surrounding the latter pipe in the chamber 18 formed by making the shaft 8 hollow or tubular, and when the water so heated is discharged through the gland means 58 by way of the pipe 60, it will have had considerable heat imparted 30 thereto, or will have taken up the heat from the pipe 17, and may be used in various ways, such as heated feed water for a boiler or for general heating purposes through circulating pipes. The compressed air discharged through the pipe 17 will be conveyed to a suitable tank in which the air may be stored and utilized as desired, or the said pipe 17 may extend away and be connected to any suitable apparatus where the 35 use of compressed air is desirable. By disposing the several units A B and C at different angles on the shaft 8 through the hubs 12, a continuous flow of compressed air will enter the pipe 17, the amount being dependent upon the speed of rotation of the shaft 8, and furthermore, the operation of the shaft will be facilitated or greatly assisted by the momentum of said units, and such governing mechanism as may be necessary will be used to control the speed of rotation of the shaft 8, and any other controlling accessories or devices that may be necessary and well known in the art may be adopted to obtain the best results. The operation 40 of the pistons 40 in the several cylinders at the ends of the units will not interfere with the operation of the said units, and the compressing force on the pistons will obviously be regulated and controlled by the weight of the intermediate sliding bodies 70 or frames 19. The cushions of buffers 32 will regularly operate against the inner ends of the cylinders 39 to check the movement of the intermediate bodies or frames 19 and eliminate shock and jar as well as wear on 75 the engaging parts, and as found necessary these cushions may be replaced by similar devices when worn and may be of any dimensions best adapted for the purpose. 80

What is claimed as new is:

1. In a mechanism of the class specified, a rotatable shaft, a compressing unit mounted on and rotatable with the shaft and having an intermediate weighted slidable body which is free to move in reverse longitudinal directions and compressing cylinders at opposite ends in fixed relation to the shaft, the cylinders being provided with intake and discharge valves working in reverse directions, pistons connected to opposite ends of the said body and movable in the cylinders, pipe connections at the outer ends of the cylinders, and a main discharge pipe extending through the shaft and to which the said pipe connections are connected, the shaft 90 having water receiving and discharging means communicating with opposite extremities thereof. 95
2. In a mechanism of the class specified, a rotatable shaft having an air pipe extending therethrough, a compressing unit mounted on and rotatable with the shaft and having compressing devices at opposite ends and an intermediate reversely longitudinally slidable weighted body having the 100 opposite ends thereof connected to and actuating the compressing devices, and pipe connections between the compressing devices and the pipe extending through the shaft, the shaft having water receiving and 105 discharging means communicating with opposite extremities thereof. 110
3. In a mechanism of the class specified, a rotatable shaft of tubular form, an air pipe extending through the said shaft and 115 beyond one extremity of the latter, a compressing unit mounted on and rotatable with the shaft and having air compressing devices at opposite extremities held in fixed relation, and a weighted reversely sliding body between said compressing devices and connected to a part of the latter for reversely charging the said devices with air and also reversely discharging air therefrom, the said devices being connected by pipes to the 120 pipe extending through the shaft, the shaft having water receiving and discharging means communicating with opposite extremities thereof. 125
4. In a mechanism of the class specified, a 130

5 ofatable tubular shaft having an air pipe extending therethrough and beyond one end of the same, an annular chamber being formed between the said pipe and the shaft, 10 an air compressing unit mounted on and rotatable with the shaft and having air compressing means at opposite extremities including pistons, a reversely sliding weighted body between the said devices and having the pistons connected thereto, pipe connections between the said devices and the pipe extending through the shaft, and water-receiving and discharging gland means communicating with opposite extremities of the 15 tubular shaft and the chamber in the latter around the pipe extending through said shaft.

5. In a mechanism of the class specified, a 20 rotatable shaft having a pipe extending therethrough, and beyond one end of the same, a plurality of compressing units mounted at different angles on and rotatable with the shaft, the compressing units being spaced apart longitudinally of the 25 shaft and each unit having compressing devices at opposite ends and an intermediate weighted body freely slideable in reverse longitudinal directions and connected and 30 actuating part of the said compressing devices to alternately charge the said devices with air and discharge air therefrom, and pipe connections between the said devices and the pipe extending through the shaft.

6. In a mechanism of the class specified, 35 a rotatable shaft having a compressed air conduit extending therethrough, the shaft rotating around the said conduit, and a plurality of air compressing units mounted on the shaft at different relative angles and 40 rotatable with the said shaft, the compressing units being regularly spaced apart longitudinally of the shaft, the compressing units having distinct pipe means connected thereto and to the pipe extending through 45 the shaft, the units acting in sequence to

compress charges of air and deliver the same into the pipe extending through the shaft.

7. In a mechanism of the class specified, a rotatable shaft having an air conveying conduit extending therethrough, water supply and discharge means at opposite ends thereof, the shaft being rotatable around said conduit, and an air compressing unit mounted on and rotatable with the shaft and having means for compressing air, the 55 air conveying conduit extending fully and unobstructedly through the entire length of the shaft and a pipe connection between the said means and the pipe extending through the shaft. 60

8. In a mechanism of the class specified, the combination of a rotatable shaft having fixed conduit means extending fully therethrough, a compressing unit mounted on and rotatable with the shaft and having automatically operating means for compressing air and including air-compressing cylinders and pistons at opposite ends in fixed spaced relation and an intermediate reversely longitudinally slideable weighted body connected 70 to the said pistons the opposite ends of the weighted body and the inner ends of the cylinders being in longitudinal alinement, and pipe connections between the said cylinders and the conduit extending through the 75 shaft.

9. In a mechanism of the class specified, a rotatable shaft having a fixed air conduit extending fully therethrough, a plurality of air-compressing units mounted on the shaft 80 and rotatable therewith and spaced apart at different angles throughout the length of the shaft, the said air conduit serving as a common discharge means for all of the compressing units and pipe connecting means 85 between the several units and the conduit extending through the shaft.

In testimony whereof I have hereunto set my hand.

JAMES F. THOMAS.
